UNITED STATES PATENT OFFICE.

OSCAR C. BEACH, OF LOS ANGELES, CALIFORNIA, ASSIGNOR TO FREDERICK W. BRAUN,
OF LOS ANGELES, CALIFORNIA.

REDUCTION-MILL.

1,185,046.

Specification of Letters Patent. Patented May 30, 1916.

Application filed May 4, 1914. Serial No. 836,099.

To all whom it may concern:

Be it known that I, OSCAR C. BEACH, a citizen of the United States, and a resident of the city of Los Angeles, county of Los Angeles, and State of California, have invented certain new and useful Improvements in Reduction-Mills, of which the following is a specification.

The invention relates to reduction mills or ore grinding mills, and particularly to relatively small capacity mills.

One of the objects of the invention is to provide a practical small capacity reduction mill for the grinding of ore.

Another object of the invention is to provide a reduction mill which may be readily adjusted to compensate for wear or to vary the degree of fineness to which the ore is ground.

Another object of the invention is to provide a reduction mill in which the various parts are readily accessible and removable.

A further object of the invention is to provide a reduction mill in which there is no loss or waste of the ore being ground.

A further object of the invention is to provide a reduction mill in which the ore is quickly and effectively ground.

The invention possesses other advantageous features, some of which, with the foregoing, will be set forth at length in the following description, where I shall outline in full that form of the invention which I have selected for illustration in the drawings accompanying and forming part of the specification, and although in such drawings I have shown only one specific form of my generic invention it is to be understood that I do not limit myself to such form because my invention may be embodied in a multiplicity of forms, each being a species of my said invention. It is also understood that by the claims succeeding the description of my invention, I desire to cover the invention in whatever form it may be embodied.

Referring to said drawings: Figure 1 is a vertical section of the reduction mill of my invention. Fig. 2 is a plan view of the upper grinding disk. Fig. 3 is a vertical

section of the upper grinding disk taken on the line A—A Fig. 2. Fig. 4 is a plan view of the lower grinding disk. Fig. 5 is a vertical section of the lower grinding disk taken on the line B—B Fig. 4.

55

The reduction mill of my invention is designed particularly for small capacity work to enable the working of ore bodies on a small scale and at a relatively low price for equipment and also may be used in laboratories for grinding samples of ore. The apparatus comprises a body portion or shell which is formed in two parts 2—3 which are removably held together by bolts 4, passing through lugs formed on the outside 60 of the parts. The lower portion 2 is provided with an upstanding annular flange 5 within which the upper portion 3 of the shell seats, so that a tight joint may be formed between the parts. The lower portion 65 of the shell is provided with legs 6 of suitable length, so that the driving mechanism may be arranged therebetween. The bottom 7 of the lower portion is inclined toward the discharge outlet 8 which is arranged at the opposite side of the mill from the drive shaft 9. Arranged in a central aperture in the bottom 7 is a bearing 12 for the vertical shaft 13, secured to the upper end of which shaft is the fly wheel 14. 70 The bearing 12 is provided with an upwardly extending portion which engages in the hollow hub 15 of the fly wheel, the depending annular wall of the hub serving to prevent the ground ore from coming into 75 contact with the bushing 20. Splined on the shaft 13 below the bearing 12 is a bevel gear 16 which is engaged by the bevel gear 17 on the driving shaft 9. The driving shaft 9 is supported in the bearing 18 80 formed on the bracket 19, and in an outboard bearing (not shown) formed on the outer end of the bracket. The bevel gear 16 is held between the bearing 12 and the bushing 21 of bearing 22 and is separated 85 therefrom by fiber washers 23. The bushing 21 projects below the bearing 22 and is provided at such projecting portion with a screw thread which is engaged by a cap 24 in which is arranged a step bearing 30 for 90 95 100

the vertical shaft. The bearing 22 is supported in a plate or spider 25 which is bolted to the legs 6 and is formed with an annular flange 26, which occurs between the hub of 5 the gear 16 and a similar flange 27 on the lower surface thereof. These flanges and the fiber washers prevent dust and dirt from coming in contact with the lower bearings, a feature which is essential in a successful reduction mill.

10 Removably secured to the fly wheel 14 is the lower or rotating horizontal grinding disk 28 which seats in an indentation in the fly wheel and which is provided with lugs 15 29 which seat in apertures of larger area in the fly-wheel. The grinding disk 28 is provided at the lower portion of its outer side with a plurality of pockets 37 having backwardly inclined rear faces, which are engaged by screws 31 arranged in ears on the fly-wheel. These screws other than serving to clamp the disk 28 to the flywheel, are employed to adjust the position of the disk on the fly-wheel in order to compensate for 25 any eccentricity of weight of the disk or fly-wheel. The screws 31 are provided with lock-nuts 31^a for locking them in the set positions.

Secured to the upper portion 3 of the shell 30 by means of bolts 32 and lugs 33, is a stationary horizontal grinding disk 34 which is provided with a central aperture which registers with an aperture 35 in the top of shell 3. The lugs and bolts engage in apertures of larger area in the shell, so that the position of the disk 34 may be adjusted, so that it may be eccentric or concentric with relation to disk 28. Arranged above the shell and secured thereto is a hopper 36, the 40 outlet of which registers with the aperture 35 in the shell. The faces of the grinding disks are in contact or lie close together and the distance between them may be varied or their wear may be compensated by rotating 45 the cap 24 in which the step bearing for the vertical shaft is arranged. By adjusting the position of the lower grinding disk with respect to the upper, different degrees of fineness of the ore may be obtained, a feature which is of great importance in ore 50 testing work. The disks are, therefore, adjustable vertically or laterally with respect to each other.

The grinding disks are provided with recessed faces, to form a pocket therebetween for the ore to be ground, the rotating disk 28 having a solid bottom and the stationary disk having a central aperture registering with the aperture 35 in the shell. The grinding 60 face of each disk comprises a succession of alternate radially disposed pockets 38 and elevations 39, both pockets and elevations increasing in width outwardly. The elevations and depressions terminate within the

smooth annular peripheral faces 41 of the 65 disks, between which faces the final grinding occurs, the elevations merging into the peripheral surfaces 41 and the indentations terminating rather abruptly at these faces. The surfaces of the elevations in the fixed 70 grinding disk 34 are curved through an arc of substantially 90°, merging at one end into the aperture 35 and at the other end into the peripheral face 41. The rotating disk is more shallow than the stationary disk 75 and the depressions therein terminate adjacent the center of the disk, providing at the central portion an elevation 42 from which the elevations 39 spring. The faces of the elevations on the two disks approach each 80 other as they progress outwardly until they virtually meet at the grinding surfaces 41.

The centrifugal action caused by the rapid rotation of the lower disk forces the ore outward and it is caught between the elevations on the disks and broken and ground into smaller particles. The particles as they are broken move outwardly and are still further broken and finally move into the space between the edges of the disks, 90 where they are ground to the desired fineness. Discharging from the disks, the ground ore falls onto the inclined bottom 7, whence it may be washed through the discharge outlet 8 by means of water entering 95 through the pipe 43. All of the ore introduced between the disks is forced outwardly and ground, and the centrifugal force of rotation forces it outward between the disks and increases the rate at which it is ground. 100

I claim:

1. In a reduction mill, a stationary horizontal grinding disk, a vertical shaft, a fly wheel attached to the upper end of said shaft, a rotatable horizontal grinding disk 105 adjustably mounted on said fly wheel and means for adjusting said rotatable disk vertically with respect to the stationary disk.

2. In a reduction mill, a vertical shaft, a 110 fly-wheel attached to the upper end of said shaft, a grinding disk mounted on said fly-wheel, means for adjusting said disk laterally with respect to said fly-wheel and for clamping it in the adjustable position, a 115 stationary horizontal disk arranged above and associated with said adjustable disk, and means for adjusting said first named disk vertically.

3. In a reduction mill, a shell, a vertical 120 shaft extending into said shell, a fly wheel attached to the upper end of said shaft, a grinding disk adjustably secured to said fly wheel, a stationary horizontal grinding disk arranged above and associated with said first named grinding disk and means for adjustably securing said stationary grinding disk to said shell. 125

4. In a reduction mill, a shell having an inclined bottom wall, a vertical shaft extending through said wall, means for adjusting said shaft vertically, a grinding disk 5 adjustably secured to the upper end of said shaft and a stationary grinding disk secured to said shell arranged above and in coöperative relation with said first mentioned disk.

In testimony whereof, I have hereunto set my hand at Los Angeles, California, this 10 25th day of April 1914.

OSCAR C. BEACH.

In presence of—
H. D. MACKINNON,
Wm. KENNEDY.
